UNITED STATES PATENT OFFICE.

JAN BARTUZEL, OF YOUNGSTOWN, OHIO.

DESIGN FOR A FLYTRAP.

Application filed March 17, 1921. Serial No. 453,153. Term of patent 14 years.

To all whom it may concern:

Be it known that I, JAN BARTUZEL, a citizen of Poland, and a resident of Youngstown, in the county of Mahoning and State of Ohio, have invented a new, original, and ornamental Design for a Flytrap, of which the following is a specification, reference being had to the accompanying drawing, forming part thereof.

The figure is a front view of a flytrap showing my new design.

I claim—

The ornamental design for a flytrap as shown.

JAN BARTUZEL.
